Primary Examiner — Karen S Acker*Assistant Examiner* — Jerry Hsu*(74) Attorney, Agent, or Firm* — Polsinelli PC(57) **CLAIM**

We claim the ornamental design for a container trailer, as shown and described.

DESCRIPTION

FIG. 1 is perspective view of a container trailer, showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

Broken lines are for illustrating unclaimed portions of the container trailer, the broken lines form no part of the claimed design.
